UNITED STATES PATENT OFFICE.

WILLIAM A. D'EGILBERT AND BEN GARLAND, OF WILLOWS, CALIFORNIA.

BULL-WHEEL CLEANER.

1,321,988.

Specification of Letters Patent. Patented Nov. 18, 1919.

Application filed November 6, 1918. Serial No. 261,355.

To all whom it may concern:

Be it known that we, WILLIAM A. D'EGILBERT, a citizen of the United States, residing at Willows, in the county of Glenn, 5 State of California, and BEN GARLAND, a citizen of the United States, residing at Willows, in the county of Glenn, State of California, have invented certain new and useful Improvements in Bull-Wheel Cleaners; and we do declare the following to be a full, clear, and exact description of the same, reference being had to the accompanying drawings, and to the characters of reference marked thereon, which form a part of 10 this application.

This invention relates to improvements in cleaning devices for the bull or drive wheel of a binder or harvester, the principal object of the invention being to produce a device 20 for keeping the bull or drive wheel of a binder or harvester clean during the operation of the same over the fields, and which will prevent the dirt and mud which accumulates on the edges of the bull wheel 25 from remaining there and possibly become passed from the wheel on to various other parts of the machinery of the binder as the wheel revolves.

This device is particularly adapted to be 30 used with binders used for rice harvesting, the growing rice requiring large quantities of water which keeps the ground in a very soft condition, which condition renders the bull wheel of the binder very liable to pick 35 up quantities of mud in its traversal of the rice field.

Another object has been to produce a cleaner for the purpose described which may readily be attached to any binder without 40 any alteration thereof.

As a third object, we have provided a simple and inexpensive device, and yet one which will be extremely efficient for the purpose for which it is designed.

45 These objects we accomplish by means of such structure and relative arrangement of parts as will fully appear by a perusal of the following specification and claim.

On the drawings, similar characters of 50 reference indicate corresponding parts in the several views.

Figure 1 is a perspective view of a binder showing our improved cleaner attached thereto.

55 Fig. 2 is a perspective view of the cleaner itself.

Referring now more particularly to the figures of reference on the drawings, the numeral 1 represents the binder having the usual bull or main supporting wheel 2. 60

The cleaner comprises a frame consisting of a pair of sleds or runners 3 suitably spaced apart a distance somewhat greater than the width of the wheel 2. These sleds are connected at both ends by bolts 4, 65 which are either provided with nuts on each side of each sled or with a sleeve or pipe spacer as indicated by 5. Secured to the under surface of the sleds and suitably positioned thereon is a pair of metal scraping- 70 plates 6, whose inner edges 7 project beyond the edges of the sleds so that the plates are spaced apart a distance very little more than the width of the bull wheel. The rear ends of the sleds are shod with iron straps 75 8, the sleds themselves being preferably constructed of wood.

On the bolt 4 at the forward end of the sleds is pivotally hung a member 9, which is provided with an eye 10 in its upper end 80 and is adapted to be hung to the frame of the binder thereby, at any suitable point on said frame forward of the wheel 2, an extension 11 being connected to the member 9 if necessary to position the cleaner correctly 85 with regard to the frame of the binder, without attaching any extra parts to the latter. The normal position of the cleaner is as shown in Fig. 1, with the forward end suspended by the member 9 and clearing the 90 ground somewhat, the rear end dragging along the ground and bearing on the shoes 8.

In operation, the cleaner is attached to the binder all the time it is traversing the fields, the mud picked up by the wheel being 95 scraped off by the plates 6 before it can be passed by the wheel on to other parts of the machinery.

From the foregoing description it will be readily seen that we have produced such a 100 device as substantially fulfills the object of the invention as set forth herein.

While this specification sets forth in detail the present and preferred construction of the device, still in practice such deviations 105 from such detail may be resorted to as do not form a departure from the spirit of the invention as defined by the appended claim.

Having thus described our invention what we claim as new and useful and desire to 110 secure by Letters Patent is:—

In combination with the bull wheel of a

binder, a cleaner therefor comprising a pair of runners positioned one on either side thereof and suitably connected together at their ends, a pair of metal scraping plates 5 independent of the runners and secured to the under side thereof and projecting inwardly a distance such that their adjacent edges are spaced slightly more than the width of the wheel, and a hanger pivotally 10 connected to the forward end of the runners

and to the frame of the binder to keep the runners clear of the ground, the rear end thereof riding on the ground, whereby the dirt collected by the wheel will be removed therefrom immediately after leaving contact with the ground. 15

In testimony whereof we affix our signatures.

WILLIAM A. D'EGILBERT.
BEN GARLAND.
